UNITED STATES PATENT OFFICE

RICHARD E. BISSELL, OF CLEVELAND HEIGHTS, OHIO, ASSIGNOR TO THOMPSON PRODUCTS INC., OF CLEVELAND, OHIO, A CORPORATION OF OHIO

POPPET VALVE

Application filed July 10, 1926. Serial No. 121,569.

The invention relates to poppet valves and, in its most specific features, to what is commonly called a tulip valve.

One object of the invention is to make provision for grinding such valves while avoiding constructions which present sharp points or edges which tend to cause pre-ignition, especially in high compression engines.

10 Another object of the invention is to provide a tulip valve head which will increase the power of the engine.

Other objects of the invention are to decrease the tendency to warpage in tulip valves, and to provide a valve which will run cooler than those heretofore employed.

The objects are attained by changing the formation of the valve heads of prior constructions as will be hereinafter explained.

20 For the purpose of exemplifying the principles of my invention, I disclose herein several embodiments of the invention, but which find their best expression in the tulip valve shown in Figure 1.

25 In the annexed drawings:

Figure 1 is a vertical section taken through a valve constructed in accordance with my invention showing the adjacent parts of the engine structure, this form being the one 30 now preferred by me.

Fig. 2 is a top plan view of the valve.

Fig. 3 is a vertical section, similar to Fig. 1, of a modified form.

35 Figs. 4 and 5 are fragmentary cross-sectional views through the upper edge of tulip valves constructed in accordance with the prior art.

Fig. 6 shows the ordinary poppet valve having a curved dome, provided with a recess in its upper face having a reentrant curve, in accordance with a feature of my 40 invention.

Fig. 7 illustrates the same idea applied to a similar valve having a flat dome.

45 Fig. 8 illustrates the same idea applied to a cup valve.

Reference will first be made to that feature of my invention relating to tulip valves and which I regard at this time as the most 50 important and which is described in Figs. 1

to 5 inclusive. In order fully to understand my invention it is necessary to consider the action of exhaust gases in the process of exhaustion by tulip valves of prior construction, which are illustrated in Figs. 4 and 5. 15 As heretofore constructed the upper edge of such valves has been either flat, as indicated at *a*, Fig. 4, or curved, as indicated at *b*, Fig. 5. In the case of the flat upper edge *a* the gases, on their way to the exit opening 60 past the valve seat, are directed laterally outwardly as indicated by arrow *c* and consequently have to make a sharp turn past the outer edge of the valve. In the case of the curved upper edge *b*, a portion of the 65 compressed gases is directed tangentially at every point of the curved surface, as indicated by arrow *d*, in consequence of which eddy currents are produced which obviously increase resistance, acting like a baffle. In 70 accordance with my invention the upper edge of the valve is downwardly and outwardly inclined toward the valve seat or exit opening, whereby the gases are given a single direction, thus avoiding a sharp 75 turn at the exit opening, as in the construction shown in Fig. 4, or the eddy currents which attend the use of the construction shown in Fig. 5.

In accordance with my invention a valve 80 stem 1 is provided with a head 2, having a valve seat 3, and a deep recess 4 in the upper face, so formed as to provide a reinforcing ring 5 at the top and a curved stream line surface 6 joining the valve seat 85 and the stem; to this extent the construction is that of the prior art known in the trade as a "tulip valve" because of its resemblance to the tulip flower. But instead of forming the upper edge of the valve flat, 90 as in Fig. 4, or curved, as in Fig. 5, I give it a downward and outward inclination, or stream line surface, as indicated at 7. This surface is preferably a section of the frustum of a cone but it may be slightly curved. 95 The inclination which will give the best results will depend upon the formation of the adjacent walls of the engine cavity in which the valve may be employed, the extreme range for all types of engines to give 100

advantageous results probably extending between 1° and 60°. The inclination shown in the drawings and which I have found most desirable in the structure shown is approximately 13°.

5 Another feature of my invention relates to the formation of the wall of the cavity 4. Prior constructions of this type have been very difficult to grind. It has been proposed to provide a screw-driver slot in the wall of the cavity 4, or small holes for the engagement of a tool, but such provisions involve the formation of sharp edges or points which heat more than plane surfaces and therefore tend to cause pre-ignition, especially in high compression engines. Such provisions also weaken the valve head, tending to permit the parts of the head to close in toward the weakened section. To 10 avoid these objections and provide an effective means for the engagement of a tool, I provide the wall of the cavity 4, near the upper edge of the head, with a reentrant curve forming an inwardly opening annular recess 8. This recess is adapted to be engaged by a special tool devised by me and made the subject-matter of an application filed August 2nd, 1926, Serial No. 126,352, whereby the head may be gripped and 15 turned for grinding purposes.

20 Another function of the recess 8 is that it increases the capacity of the cavity to retain dead gases and hence decreases the flow of heat to the valve for which this cavity is 25 in part designed.

25 Still other advantages flowing from this construction are that it forms a rigid, non-deforming ring at the top of the head, thereby tending to prevent warpage, at the same 30 time decreasing the weight of the valve.

35 The feature just described also may be applied to valves of other types. In Fig. 6 there is shown a poppet valve having a curved dome, provided with a recess 9 with 40 the reentrant curve 8 in the wall. In Fig. 45 7 is illustrated the idea applied to a valve with a flat dome, while Fig. 8 shows it applied to a valve of the cup type. When the invention is applied to the constructions 50 shown in Figs. 6 and 7 it presents the advantages that the surface is smooth throughout, thus avoiding hot spots, the head is lightened, and a dead gas space is created.

55 It is obvious that various changes may be made in the structure disclosed without departing from the principles exemplified therein. It is therefore to be understood that my invention is not confined to the details described, but that it includes all 60 changes and modifications falling within the terms of the appended claims.

65 What I claim is:

1. A tulip valve having its upper edge outwardly and downwardly inclined toward the valve seat and a reentrant curve in the

wall of the central cavity near the upper edge.

2. As a new article of manufacture, a tulip valve having an inwardly projecting annular lip disposed about the periphery of its central cavity to convert the central cavity into a gas retaining pocket.

3. As a new article of manufacture, a valve having its head provided with a central recess and an annular ridge extending inwardly about the periphery of the recess to convert the recess into an effective gas retaining pocket.

4. As a new article of manufacture, a valve having its head provided with a central recess, the top edge of the recess having a flat downwardly sloping stream line surface, and an annular ridge extending inwardly about the periphery of the recess.

Signed by me this 2 day of July, 1926.

RICHARD E. BISSELL.
